PAD LOCK BOLT

Carl Arthur Boys Lindop, Willenhall, England

Application July 27, 1956, Serial No. 42,463

Term of patent 14 years

(Cl. D10—5)

Fig. 1.

Fig. 2.

Fig. 3.

I claim:

The ornamental design for a pad lock bolt, as shown.
